UNITED STATES PATENT OFFICE.

WILLIAM F. CAPITAIN, OF CHICAGO, ILLINOIS.

DESIGN FOR A FONT OF PRINTING-TYPE.

SPECIFICATION forming part of Design No. 16,106, dated May 26, 1865.

Application filed February 19, 1865. Term of patent 25 years.

To all whom it may concern:

Be it known that I, WILLIAM F. CAPITAIN, a citizen of the United States of America, residing at Chicago, in the county of Cook and State of Illinois, have invented and produced 5 a new and original Design for a Font of Printing-Type, of which the following is a specification, reference being had therein to the accompanying printed specimens.

My invention consists of a new design for a 10 font of printing-type composed of vertical letters formed of lines of uniform thickness, having no ceriphs, except H in the word "THE." The upper portions of the capital letter A and the lower portions of the capital and lower-case letters v and w are formed of 15 horizontal lines having angular connections with the side lines of these letters. The front lines of one form of the capitals A, H, M, and R and the lower-case letters h, m, and n extend 20 below the back lines of these letters. The cross-lines of the capitals A and H are V shape, the sides of which extend from the central angle to but not across the side lines 25 of the letters.

The large letters C, D, G, O, and Q and the small letters b, c, d, h, m, n, o, p, q, r, and u are all formed with scrolls within the letters, and within the large letters C and G are 30 scrolled lines, the upper ends of which connect with the terminal ends of the scrolls of these letters.

The word "AND" is inclined, the back end 35 of the word being raised above the horizontal line, and the left line of A is extended under

the word and terminates with a backward horizontal line, and the line forming the curved portion of D is extended over the word and terminates in a horizontal forward line.

In the abbreviation "Co." the o is formed 40 inside of and interlocks with the upper scroll of the letter C.

The H in the word "THE" is provided with upper and lower ceriphs extending the 45 whole length of the word, the back vertical line of H being connected with the lower but not with the upper ceriph, and the front vertical line being connected with the upper but not with the lower ceriph, and the letters T and E are formed between the ceriphs. 50

What I claim as new, and desire to secure by Letters Patent, is—

The design for a font of printing-type in which the side lines of A, V, W are connected by horizontal straight lines; the front lines of one form of A, H, M, R, h, m, and n extend 55 below the back lines; the cross-lines of A and H are V shape, extended from the center upward to but not across the side lines; C, D, G, O, Q, b, c, d, h, m, n, o, p, q, r, and u are formed 60 with scrolls, these and the other portions of the design being substantially as described and shown.

In testimony whereof I have affixed my signature in presence of two witnesses.

WILLIAM F. CAPITAIN.
